Primary Examiner — Jeffrey D Asch*Assistant Examiner* — Tracey J Bell*(74) Attorney, Agent, or Firm* — Panitch Schwarze Belisario & Nadel LLP(57) **CLAIM**

The ornamental design for a mobile telephone, as shown and described.

DESCRIPTION

FIG. 1 is a front perspective view of a mobile telephone in accordance with my new design;

FIG. 2 is a front view thereof;

FIG. 3 is a rear view thereof;

FIG. 4 is a top plan view thereof;

FIG. 5 is a bottom plan view thereof;

FIG. 6 is a left-side elevational view thereof; and,

FIG. 7 is a right side elevational view thereof.

The broken lines in the figures depict portions of the mobile telephone that form no part of the claimed design.
